UNITED STATES PATENT OFFICE.

ANDREW M. MORRISON, OF DUBUQUE, IOWA.

SANITARY PLUMBING CONNECTION.

No. 901,545.

Specification of Letters Patent.

Patented Oct. 20, 1908.

Application filed October 22, 1906. Serial No. 389,946.

To all whom it may concern:

Be it known that I, ANDREW M. MORRISON, a citizen of the United States, and a resident of the city of Dubuque, in the county of Dubuque and State of Iowa, have invented certain new and useful Improvements in Sanitary Plumbing Connections; and I do hereby declare that the following is a full, clear, and exact description of the same, reference being had to the accompanying drawings, and to the letters of reference marked thereon, which form a part of this specification.

Heretofore in connecting various fixtures, as for instance a water closet, with a soil pipe, lead pipe has been employed and careful measurement has been required to properly locate the closet and a skilled plumber is always necessary inasmuch as the lead joints must be wiped. Furthermore when connected in this manner considerable time is consumed on each joint thus rendering such constructions unnecessarily expensive. Furthermore should the joint become defective it can only be repaired and at considerable expense by one especially skilled at such work.

The object of this invention is to afford a connection between various fixtures and the soil pipe whereby the use of lead piping is entirely obviated and instead cast iron pipe with calked joints are used.

It is a further object of the invention to afford a construction in which the pipe section or sections connecting the soil pipe with the closet, is united both with the soil pipe and with the closet connection by slip joints thereby avoiding the necessity for exact measurement.

It is a further object of the invention to so connect the pipes as to enable the slip joints to be calked externally at the closet end of the connection.

The invention consists in the matters hereinafter described and more fully pointed out and defined in the appended claims.

In the drawings: Figure 1 is a vertical section of a device embodying my invention. Fig. 2 is a section taken on line 2—2 of Fig. 1. Fig. 3 is a section taken on line 3—3 of Fig. 1. Fig. 4 is a reduced side elevation partly in vertical section showing a plurality of tees connected by slip joints to receive the battery of closets discharging to the soil pipe. Fig. 5 is a similar view but showing the sani-

tary tees laid upon their sides and connected by slip joints. Fig. 6 is a fragmentary sectional view of the cast elbow. Figs. 7 and 8 illustrate a joint formed in the soil pipe.

As shown in the drawings: A indicates a sanitary tee of novel construction in which as shown the discharge end *a* is reduced in size as is usual and the longitudinally alined receiving end is of such diameter as to receive the receiving end *A'* of the corresponding tee to afford a slip joint therewith. A branch *a*³ in which fits the longer end of an elbow *C* or *C'* which may extend nearly the entire length of the branch is enlarged at the outer end to afford a hub to receive the oakum and lead calking which closes the joint. Stops *a*⁴—*a*⁵ are provided in the branch *a*³ and in the receiving end *a'* of the tee near the inner end of the branch to limit the inward adjustment of the pipe ends received therein to prevent the same obstructing the flow.

In connecting with closets, the floor *B* is cut to provide a relatively large aperture therethrough and a pipe *B'* which may be of any desired length extends downwardly into the upwardly turned end *C'* of said elbow in which is provided a stop *c* to prevent said pipe *B'* obstructing the flow. Said upwardly turned end *C'* is calked around the pipe *B'* to afford a tight joint. Said end *C'* of the elbow may be of any desired length so that said pipe *B'* engaged therein permits relative adjustment of the parts before calking and is screw threaded at its upper end to engage in a collar *b* which is bolted to the floor and on which the closet sets and is secured. Said tubes or pipes *B'* may be constructed of the same or different lengths but the ends *C'* of the elbow are constructed sufficiently long to permit the relative adjustment of the parts before calking.

Said construction as shown affords a slip joint corresponding with that at the opposite end of the elbow and permitting packing before the collar *b* is screwed upon the upper end of the pipe or tube *B'*.

As shown the elbow *C* is tapped and provided with screw plugs one on each side thereof beneath the upturned end *C'* and also a little above the axis in the bend. Said plugs are indicated by *c*²—*c*³. Said elbow is of course usually cast metal and may be provided with hubbed apertures instead of threaded, as shown in Fig. 6, in which the el-

bow C² is plugged by means of the stops c⁶—c⁷ which are calked with lead and oakum the same as the slip joints. Said apertures afford means for attaching either a vent pipe 5 or the waste pipe or pipes from any other fixtures if desired.

In the construction shown in Fig. 4 a plurality of tees A² are connected by inserting the reduced discharge end on one into the receiving end of the other forming slip joints and arranging said tees on their backs with the branches a³ directed upwardly and adjusting the pipes B' therein to afford slip joints elevating the inner end of said pipes 15 sufficiently to insure the flow to the soil pipe.

In the construction in Fig. 5 sanitary tees A² such as before described are connected by inserting the discharge end of one into the receiving end of the other with the branches extending laterally therefrom. Said tees are arranged upon their sides and the branches a³ of each extend parallel with their outer ends in alinement and into each 20 extends the long end of an elbow C as before described thus enabling any desired number of closets to be arranged in battery if desired, and owing to the construction of said tees enabling the same to be adjusted relatively of each other owing to the slip joint 25 connections for the tees—the tees and elbows and the elbows and closet pipe.

The operation is as follows: In connecting said fittings many different variations of adjustment are possible. The soil pipe having 30 been erected in suitable position the closets if single may be connected therewith by means of the tee and an elbow. If in battery, tees either with or without the elbows are used or Y's may be used. Inasmuch as the 35 upwardly turned end of the elbows when used or of the tees when connected as shown in Fig. 4 afford a hub to receive the oakum and lead for calking, and inasmuch as said upwardly turned end is of such length, the same 40 may be adjusted relatively of the pipe B' as desired to insure the requisite fall to the soil pipe and the proper fit within the branch. Owing to the presence of the stops within the 45 flow can never be obstructed by the connecting part projecting into the passage. Inasmuch as said tube B' may be made of any desired length as may also the part connecting therewith where the space between the ceiling and the floor is very small and also where 50 the space is considerable and obviously in calking the joints formed by the pipe B' and the shorter end C' of the elbow or the upturned branches of the tees all the calking is done externally and there is nothing to afford 55 lodgment or to be contaminated by the waste to the soil pipe.

Should a slip joint not be desired in the soil pipe a ring a⁶ may be inserted in the hub to stop the end of the succeeding tee and the 60 packing therefor as shown in Fig. 8.

Owing to the simplicity of the construction a single workman can install many closets in the course of an ordinary working day and when installed the construction is much more satisfactory and sanitary than where connected 70 by methods heretofore used.

While I have described my invention as applied to connecting closets with soil pipes obviously the same is adaptable for use for other purposes and I do not purpose limiting 75 this application for patent otherwise than necessitated by the prior art as many details of construction may be varied without departing from the principles of my invention.

I claim as my invention:

1. In a device of the class described the combination with a main waste pipe having a lateral branch provided with a hubbed end, a stop in said branch, an elbow having a long end affording a slip joint with the branch, 80 affording space for calking and limited by the stop from extending into the main waste passage, said elbow at its opposite end provided with a hub and having apertures for waste and vent connection, plugs adapted 85 to be threaded into said apertures, a pipe or sleeve affording a slip joint with the hubbed end of said elbow and a flange threaded upon the upper end of the sleeve adapted to be engaged to the floor to secure said sleeve in 90 alinement with the outlet aperture of the fixture.

2. In a device of the class described a sectional cast waste pipe for water closets embracing a straight tubular section supported 100 at its upper end on the floor and opening therethrough and a tubular cast section affording a slip joint connection with said pipe and having its end directed at an angle therewith and affording a slip joint with the 105 soil pipe and opening laterally in the latter, said cast section having hubbed ports for connection with vent and waste pipes and plugs calked in and closing said ports when not connected with a soil or vent pipe. 110

3. In a device of the class described the combination with a sanitary tee adapted for connection with a soil pipe of a sanitary elbow having at one end a long hub and the other end being plain for engagement in the 115 waste pipe and a stop within the short end of the elbow just above the head.

4. In a device of the class described the combination with the soil pipe having a laterally directed branch, of a main waste 120 pipe opening into said branch and affording a slip joint therein and comprising a plurality of similar sanitary fittings each affording a slip joint in the other, a hubbed branch on each, pipes extending through the floor 125 into the branch past the hub affording a space for calking and affording a slip joint in each branch, means limiting the movement of each pipe thereby preventing the same from projecting into the main waste 130

passage and a collar secured on each pipe and affording a tight joint and adapted to bear on the floor.

5. In a device of the class described the combination with a tee having a long hub on one end, of a branch engaged thereto having a hub on its outer end, a stop in said branch, a stop in said hubbed end, an elbow adapted to telescope said branch and afford 10 a slip joint therewith, and having oppositely disposed apertures at the bend and an aperture at the axis thereof, a plug adapted to close each aperture, a stop in said elbow above said axial aperture and a pipe adapted 15 to fit around the closet-bowl and afford a slip joint with the upturned end of the elbow.

6. In a device of the class described the combination with a sanitary tee having its alined ends of different diameter, a branch 20 opening intermediate the same, an inwardly projecting stop in the branch, a stop in the lower of said alined ends, an elbow affording a slip joint with the branch having apertures for vent or soil connections at the bend,

one of which is on a different plane from the 25 others and an internal stop at the bend of said elbow.

7. The combination with a sanitary tee having its alined ends of different diameters, an elongated hub on one end adapted to receive calking and to afford a slip joint with its connection, an internal stop below said hub, an external flange on the opposite end adapted to fit within a hubbed connection and to support the calking, a branch opening intermediate said ends, a stop therein, an elbow affording at one end a slip joint with said branch, a pipe affording a slip joint with the upturned end of said elbow and a stop at the bend of said elbow. 40

In testimony whereof I have hereunto subscribed my name in the presence of two subscribing witnesses.

ANDREW M. MORRISON.
